UNITED STATES PATENT OFFICE

148,245

DESIGN FOR A WASHBASIN

Basil E. Jones, Flossmoor, Ill., assignor to The Pullman Company, Chicago, Ill., a corporation of Illinois

Application March 30, 1946, Serial No. 128,116

Term of patent 14 years

(Cl. D4—2)

To all whom it may concern:

Be it known that I, Basil E. Jones, a citizen of the United States, residing at Flossmoor, in the county of Cook and State of Illinois, have invented a new, original, and ornamental Design for Washbasin, of which the following is a specification, reference being had to the accompanying drawings, forming part thereof.

Fig. 1 is a general perspective view of my new design for a washbasin arrangement showing the washbasin with the cover thereof in the lowered position;

Fig. 2 is a top plan view of Fig. 1;

Fig. 3 is a top plan view of Fig. 1 with the cover in its raised position showing the washbasin arrangement and with portions of the cover on both sides of the water faucet broken away to show the water faucet and its control valve handle;

Fig. 4 is a general perspective view of the washbasin similar to Fig. 1 but with the cover raised;

Fig. 5 is a front perspective view similar to Fig. 4;

Fig. 6 is a sectional view through the washbasin taken along the line 6—6 of Fig. 3 showing the contour of the bowl portion of the basin; and

Fig. 7 is a sectional view through the washbasin taken along the line 7—7 of Fig. 2 showing the contour of the bowl and the faucet and faucet control arrangement.

The dotted line representations in the several figures of the drawings are for illustrative purposes only.

What is claimed is:

The ornamental design for a washbasin, substantially as shown and described.

BASIL E. JONES.
